United States Patent Office.

JOHN PLAYER, OF NORTON, ENGLAND.

Letters Patent No. 65,599, dated June 11, 1867; patented in England April 21, 1866.

IMPROVED HOT-BLAST STOVES.

The Schedule referred to in these Letters Patent and making part of the same.

TO ALL WHOM IT MAY CONCERN:

Be it known that I, JOHN PLAYER, of Norton, near Stockton-on-Tees, in the county of Durham, in England, have invented new improvements in Hot-Blast Stoves, or apparatus for heating blast for smelting iron; and I do hereby declare that the following is a full and exact description thereof, reference being had to the accompanying drawings, and to letters of reference marked thereon.

This invention has for its object improvements for heating stoves, or apparatus for heating blast for smelting iron in blast furnaces in which coal or coke is used as a fuel or for heating the blast. Whereas in the specification of a patent granted to me, and dated the 29th day of March, 1865, I have described a method of using the waste gases from blast furnaces with closed tops; and whereas a great number of blast furnaces are still working with open tops and heating the blast with coal fires or the gas drawn from the furnace top by means of a high stack; and whereas the proprietors of such furnaces cannot avail themselves of the full advantages of the use of my said patent: now this invention has for its object improvements in the arrangement of stoves by which a very high temperature may be given to the blast; and all the advantages of my former patent derived except the saving of fuel, which accrues where closed top furnaces are used. Whereas it has been the custom, in heating blast in cast-iron pipes with a coal fire, to have the fire-place arranged generally under the pipes to be heated, and to form an integral part of the so-called heating-stove; and whereas by this arrangement the flame and smoke from the coal fire pass directly amongst and impinge on the pipes through which the blast to be heated passes, and acts injuriously on the said pipes; and whereas, although in some instances arches were placed over the fire-places, with a view to prevent the great heat of the fire from acting injuriously on the pipes, the flame nevertheless was not prevented from acting injuriously on the pipes: now this invention provides a remedy for this disadvantage. The heating-stove is divided into three distinct compartments, that is to say, first, a fire-place or furnace built by preference very similar to the fire-place of a puddling furnace; secondly, immediately adjoining the furnace is a combustion-chamber, into which the flame and smoke from coal inside the first-mentioned furnace pass; thirdly, immediately above this chamber, or contiguous to it, is another, separated by a thick arch of brick-work, in which are certain apertures through which the heated fumes formed in the combustion-chamber pass. In this upper chamber is placed the system of cast-iron pipes through which the blast to be heated travels. The upper chamber is of large dimensions as compared to the space occupied therein by the system of pipes in which the heating of the blast takes place; this causes the upper chamber to be at all times pervaded by a red-hot atmosphere, which acts on all parts of the system of pipes alike.

Figure 1 of the annexed drawings is a side elevation of a hot-blast stove constructed according to my invention.

Figure 2 is an end elevation.

Figure 3, a longitudinal section.

Figure 4, a transverse section; and

Figure 5 is a plan of the same.

Figure 6 is a horizontal section taken at the line 1 1, fig. 3.

Figure 7 is a horizontal section taken at the line 2 2, fig. 3; and

Figure 8 is a horizontal section taken at the line 3 3, fig. 3.

a a is the furnace or fire-place. *b b* is the combustion-chamber into which the flame and smoke from the furnace *a* pass and there complete their combustion. *c c* is a substantial arch of fire-brick closing in the top of the chamber *b*. *d d* is the upper chamber, containing the cast-iron pipes in which the blast to be heated circulates. This chamber receives a glowing atmosphere from the lower chamber *b* by the passages *b' b'*, in the top of the arch *c*, and also by the side passages *e e*. At the top of the chamber *d* is a chimney, *f*, fitted with a damper at the top. *g* is a pipe of rectangular section by which the blast to be heated is led to the stove; it has a regulating valve at *g'*. *h* is a corresponding pipe by which the blast passes away from the stove. On these pipes are sockets to receive the ends of inverted *U* pipes. *i i* are short troughs, also rectangular section, also passing across from the pipe *g* to the pipe *h*. They are closed at their ends, and have a central partition, and also sockets for *U* pipes at the top. *k k* are the *U* pipes fitted into the sockets in the

pipes *g* and *h* and in the troughs *i*. They are so arranged, as will be seen, that each row of U pipes affords a free passage for the pipe *g* to the pipe *h*, but in passing it is compelled to ascend and descend three times, so that it may pass over a large extent of heating surface. At the top of each limb of the U pipes is an opening to facilitate the removal of the cores from the pipes after casting. These openings are closed by stoppers when the stove is at work.

I prefer to use in connection with these stoves a jet of steam passed into the incandescent fuel or flame therefrom in such a manner that the steam is mixed in the combustion-chamber with the gases in ignition, and thereby becomes highly superheated, and in this state passes on into the upper chamber, thus conveying and distributing heat amongst the pipes to be heated through which the blast travels. The effect of this steam jet is threefold: in the first place, it draws the gases from the fire-places before described into the combustion-chamber; secondly, the steam here mixes with the flame produced by ignition and prevents its attaining a too high temperature; and thirdly, it is used as a medium to carry the heat generated into the upper chamber. There are these steam jets for a stove of the size shown. The orifices may conveniently be about three-eighths to half an inch diameter, by pressure of the steam being, say, thirty pounds on the inch. A regulating cock is applied in connecting with each steam jet. Another method of using the steam jet according to my invention is to employ it to draw down gases from the top of a blast furnace through, or to force the said gases into, the stove for heating the blast, when they are burnt with or in the place of solid fuel. The arrangement at the top of the blast furnace may be similar to arrangements heretofore employed for drawing off gases from open blast furnaces; these may be apertures in the sides of the brick-work, a few feet below the surface of the charge, and these openings may lead into a circular flue surrounding the furnace, from which flue the gas pipe descends, or the end of the gas pipe may simply be inserted a few feet down into charge in the furnace. The stove does not require to be modified, except that the two branch gas pipes *m m* are added, as is shown in Figure 9, which is a portion of the horizontal section of the stove, and in Figure 10, which is a portion of a plan of the same. These gas pipes have nozzles, as shown, say about six inches' diameter, and these nozzles enclose within them the steam jets, and the jets then act to produce a partial vacuum in the gas pipe, which is immediately supplied by more gas from the blast furnace. The gas drawn by the jets from the gas pipe is thus forced into the stove and is there burnt, or the steam jet may be placed on the top of the stove, and thus a partial vacuum formed therein. The gas in this case is burned without a mixture of steam.

What I claim is the constructing and arranging a hot-blast stove, to be used with coal or solid fuel, with three distinct chambers, in the manner herein described.

Also, the use in conjunction therewith of a steam jet as herein described.

I also claim the use of a steam jet to draw down gases from the top of the blast furnace, or to force it into the stove for heating the blast.

In witness whereof I, the said JOHN PLAYER, have hereunto set my hand this 18th day of October, 1866.

JOHN PLAYER.
